UNITED STATES PATENT OFFICE.

JOHN C. SPEIRS, OF WORCESTER, MASSACHUSETTS, ASSIGNOR TO THE LOCOMOBILE COMPANY OF AMERICA, OF NEW YORK, N. Y.

DESIGN FOR AN ENGINE-FRAME.

SPECIFICATION forming part of Design No. 32,749, dated May 29, 1900.

Application filed April 25, 1900. Serial No. 14,358. Term of patent 14 years.

To all whom it may concern:

Be it known that I, JOHN C. SPEIRS, of Worcester, in the county of Worcester and State of Massachusetts, have invented and 5 produced a certain new and original Design for an Engine-Frame, of which the following is a specification, reference being had to the accompanying drawings, forming a part thereof.

10 My design relates to the side frame of an engine, and is shown in the accompanying drawing, which represents a perspective view of the frame.

The invention consists in the novel configuration imparted to the frame 1. (Shown in 15 the drawing.) At the top of the frame is a horizontal ring 2, from opposite points on the lower side of which project two arms 3. At the lower ends of said arms 3 the frame takes

a lateral bend, forming a horizontal shelf 4, 20 and then continues downwardly to form a substantially-triangular lower part 5, the upper base of which coincides with the upper edge of the shelf 4. At the lower apex of the triangular portion 5 is a vertical ring 6. 25 At the upper apexes of the triangle, on the ends of the shelf 4, are two parallel horizontal shoulders or enlargements 7.

I claim—

The design for an engine-frame, substantially as herein shown and described.

In testimony whereof I have affixed my signature in presence of two witnesses.

JOHN C. SPEIRS.
